PHASE MODULATION RECEIVING SYSTEM

Bertram Trevor, Riverhead, N. Y., assignor to
 Radio Corporation of America, a corporation of
 Delaware

Application June 24, 1943, Serial No. 492,037

5 Claims. (Cl. 250—20)

My present invention relates to radio receiving systems adapted for receiving phase modulated carrier wave energy, and more particularly to a frequency modulation receiving system particularly designed for receiving phase modulated carrier waves.

As is well known, phase modulated carrier waves are generated in a manner similar to the generation of frequency modulated carrier wave energy in that in both phase and frequency modulation, a predetermined carrier frequency is deviated in response to variations in amplitude of the modulation signals, and the rate of frequency deviation is a function of the modulation frequencies. In the case of phase modulation the higher modulation frequencies are emphasized more than in frequency modulation. Assuming that the modulation signals are of audio frequency, in phase modulation there is a greater frequency deviation of the carrier for the higher audio frequencies than for the lower frequencies, and this frequency deviation is proportional to the modulating frequency.

At the receiving system, therefore, the audio amplifier frequency response is deliberately de-emphasized for the upper audio frequencies where phase modulated carrier wave energy is received with a frequency modulation receiver. Indeed, in past methods of receiving phase modulated carrier waves it has been customary to utilize de-emphasis proportional to the audio frequency in the audio network of the receiving system. The overall result of such de-emphasis at the receiver is to provide for the combined transmitter and receiver systems a substantially flat audio response down to the lowest frequency covered by the de-emphasis circuit. Due to the nature of the de-emphasis circuit, however, a loss of gain of about 5:1 is obtained even at the lowest audio frequencies employed.

It may, therefore, be stated that it is one of the main objects of my present invention to provide a frequency modulation receiver capable of receiving phase modulated carrier wave energy, the modulation signal utilization network being constructed and arranged so as to provide an output which is inversely proportional to the modulating frequency, but wherein there is substantially no loss of gain for the lowest useful modulation frequencies.

Another important object of this invention is to provide a receiver of angle modulated carrier wave energy whose modulation signal utilization network is provided with at least two cascaded resistance-capacitance compensation networks;

one of the compensation networks being adapted to reduce the higher modulation frequency response, while the other compensation network functions to emphasize the lower modulation frequency response which is not affected by the first-named compensation network.

Still another object of my invention is to provide an audio frequency amplifier network which has a first resistor-capacitor network functioning to cause the high frequency response to be inversely proportional to frequency, and a second resistor-capacitor network acting to render the low frequency response inversely proportional to frequency down to the lowest modulation frequency desired to be reproduced.

Yet another object of this invention may be stated to reside in the provision of a flat-gain, audio frequency amplifier circuit, particularly adapted for amplifying the compensated audio output of an audio network of the type described above, and the flat-gain amplifier essentially comprising an output tube of the cathode follower type which degeneratively feeds back audio voltage to a cathode of an earlier tube.

Still other objects of my invention are to improve generally the response characteristics and efficiency of frequency modulated receivers when used to receive phase modulated signals, and more especially to provide compensated audio networks for such receivers in an economical and reliable manner.

The novel features which I believe to be characteristic of my invention are set forth with particularity in the appended claims; the invention itself, however, as to both its organization and method of operation will best be understood by reference to the following description, taken in connection with the drawings, in which I have indicated diagrammatically several circuit organizations whereby my invention may be carried into effect.

In the drawings:

Fig. 1 is a circuit diagram of one embodiment of the invention,

Fig. 2 graphically illustrates idealized characteristics of prior frequency modulation receivers,

Fig. 3 graphically shows by means of idealized curves the functioning of the compensation networks of this invention,

Fig. 4 shows a modified form of the invention.

Referring now to the accompanying drawings, wherein like reference characters in the different figures designate similar circuit elements, the numeral 1 denotes the detector network of a conventional frequency modulation receiver. The

generic term "angle modulated carrier wave" is to be understood as broadly including frequency modulated, or phase modulated, carrier wave energy. Those skilled in the art are fully aware of the manner of constructing a frequency modulation ("FM" for brevity hereinafter) receiver. Therefore, it is not believed necessary to disclose the various transmission networks which precede the FM detector 1. Reference is made to U. S. Patent No. 2,121,103 granted June 21, 1938 to S. W. Seeley, disclosing and claiming a well-known form of FM detector circuit that may be utilized to derive the modulation signals from FM wave energy.

It is known that the FM detector 1 may be immediately preceded by an amplitude modulation limiter stage. Furthermore, let it be assumed that the various selector networks of the receiver are designed to pass FM waves having an overall frequency deviation of at least 150 kilocycles (kc.). Of course, the invention is not limited to this specific deviation range, since it is equally applicable to various frequency deviation ranges. Those skilled in the art are fully aware of the fact that certain systems of transmitting FM wave energy deliberately pre-emphasize the higher modulation frequencies by causing the frequency deviation of the carrier to be greater at the higher modulation frequencies. In phase modulated ("PM" for brevity hereinafter) systems the pre-emphasis of the higher modulation frequencies inherently takes place.

Accordingly, in the prior art it has been the usual practice to provide a series resistor-condenser network across the output load of the FM detector circuit when phase modulated signals are to be received with a frequency modulation receiver. This resistor-condenser network functioned to compensate for the pre-emphasis at the transmitter. The compensation network actually discriminated against the higher modulation frequencies, and was for this reason referred to as "de-emphasis." Reference to Fig. 2 shows the pertinent idealized characteristics of prior FM receivers, and it will be observed that the effect of the pre-emphasis and de-emphasis characteristics was to provide a compensated output. In order for the de-emphasis circuit to give proper compensation, the series resistance should be at least five times the reactance of the condenser even at the lowest useable audio frequency. This gave a 5:1 loss of gain at this lowest frequency.

According to my invention the single de-emphasis network is replaced by a pair of cascaded compensation networks. One of these networks provides the characteristic shown by the solid line R_2-C_2 in Fig. 3. The other compensation network provides the overlapping characteristic represented by the dotted line R_1-C_1 in Fig. 3. (The dash symbol between the R and C letters employed above and hereinafter is not a minus sign, but merely signifies the physical combination of the respective resistance and capacity.) The overall effect of these two compensation networks is to eliminate the loss of gain at the lower audio frequencies, and still have the audio output inversely proportional to modulating frequency. In other words, one of the compensation networks reduces the high modulation frequency response in the usual manner, while the other compensation network emphasizes the lower modulation frequency response in such a manner as to give a net response inversely proportional to frequency.

Considering the specific circuit elements for accomplishing the aforesaid functions, reference is made to resistor R_1 which is arranged in series with condenser C_1 across the detector output terminals. The constants of these series resistor and capacitor elements are so chosen that there results a marked decrease of higher modulation frequency response. This is indicated by the dotted line which is referred to as R_1-C_1 in Fig. 3. The control grid 2 of the following audio amplifier tube 2' is connected to the junction of resistor R_1 and condenser C_1 . The audio amplifier 2' is of the usual construction, and specifically employs a tube of the pentode type. The screen grid of the tube is connected to the positive terminal of the direct current source (not shown) through a resistor 3. The anode, or plate, of tube 2' is connected to the positive terminal +B of a suitable direct current source through a pair of resistors R_2 and R_3 arranged in series. The lower end of resistor R_2 is connected to ground through condenser C_2 . The grid 2 requires a direct current return resistor to ground. This would normally be included in the FM detector load circuit. If this is not done, a grid leak resistor from grid 2 to ground is required. In that case the leak resistor value would have to be at least five times the reactance of condenser C_1 at the lowest compensation frequency of the network.

The series resistor-condenser network R_2-C_2 acts as the second compensation network. This compensation network has the response characteristic indicated by the solid line referred to as R_2-C_2 in Fig. 3. The network R_1-C_1 causes the higher modulation frequency response to be inversely proportional to frequency. The compensation network R_2-C_2 , however, causes the lower modulation frequency response to be inversely proportional to frequency down to the frequency where the ohmic impedance, i. e., resistance, of resistor R_3 remains greater than about five times the reactive impedance of condenser C_2 . It is assumed that the screen and cathode bypass capacitors of tube 2' are of suitable size for the audio frequency band used.

Generally speaking, the product of R_1 and C_1 should be equal to the product of R_2 and C_2 on the assumption that R_3 is much larger than the reactance of condenser C_2 , and the impedance of the compensation network R_2-C_2 is much less than the plate resistance of tube 2'. In Fig. 3 there is, also, shown the overall response or "Corrected audio output" curve, and by way of contrast the "Uncorrected audio output" curve. In the prior art using the compensation network R_1-C_1 it is required that the resistance R_1 be at least five times greater than the reactive impedance of condenser C_1 at the lowest useful audio frequency. This requirement must be fulfilled in order that the compensation be correct for all audio frequencies above the lowest used. This arrangement thereby inherently gives a five-to-one loss in gain at this lowest frequency. In the present invention, referring to Fig. 3, the compensation circuit R_1-C_1 meets this 5:1 impedance ratio at a frequency of approximately 1,000 cycles, which is considerably above the lowest useful frequency of 400 cycles. Hence, the loss in gain of 5:1 occurs at about 1,000 cycles, and is much less than this at the lower limit of 400 cycles. In other words, this circuit does not properly compensate the range below 1,000 cycles. In order to effect compensation in this range, the second compensation circuit

in the plate of tube 2' is supplied. This network operating in the plate circuit of tube 2' serves to raise the gain of the audio frequencies between 1,000 and 400 cycles in such a manner as to effect proper compensation. In other words, R₁—C₁ de-emphasizes the higher audio frequencies, whereas R₂—C₂ emphasizes the lower audio frequencies in such a manner as to give the desired compensation.

In the curve sheet shown in Fig. 3, the net compensation response curve can be considered to be the curve R₂—C₂ to the left of 1000 cycles and continuing to the right of 1000 cycles into R₁—C₁. The curve labeled "Response inversely proportional to frequency" is the theoretical compensation curve desired which will never reach the zero audio frequency ordinate line. The actual compensation curve will be as shown at R₂—C₂. The curve R₂—C₂ fails to conform with the theoretical curve at the very low frequencies, because of the interfering effect of the resistor R₃. The lowest frequency for which overall compensation is provided is 400 cycles. R₃ should have a very high value of resistance thereby to allow R₂—C₂ to operate theoretically perfect. Hence, R₃ is not a part of the compensation network R₂—C₂.

The modulation signal voltage output of tube 2' is preferably applied to an audio amplifier having a substantially flat frequency response characteristic. The purpose of the latter characteristic is to insure presentation of the modulation signal energy to the reproducer with a flat audio response. Of course, any well-known type of flat gain amplifier may be employed. It is to be clearly understood that the present invention is not limited to the specific audio amplifier system shown in Fig. 1 coupled to the output terminals of the compensation network R₂—C₂. However, since I have found the specific audio amplifier shown of desirable characteristics the present disclosure includes such specific circuit.

The audio voltage at the plate end of resistor R₂ is applied to the input grid of an audio amplifier 4. The construction of the latter is of generally well-known form. The amplifier stage including tube 4 is of the conventional resistance-condenser coupled type. Degenerative audio voltage feedback is provided to the cathode of tube 4 by connecting the lower end of the bypassed cathode biasing resistor 5 to the junction of a pair of series-arranged resistors 6 and 7. These resistors are arranged in the cathode circuit of power output tube 14. The feedback lead 8 connects the lower end of bias resistor 5 to ground through the resistor 7. The amplified audio voltage developed across the plate resistor 9 is applied to the input grid of the following audio amplifier tube 10. The cathode of tube 10 is connected to ground through an unbypassed resistor 11.

Tubes 4 and 10 may be of the 6J5 type, although other types of tubes suitable for the particular purpose may be employed. The plate of tube 10 is connected to a positive potential point through a series path consisting of resistor 12 and high frequency equalizing coil 13. The audio voltage developed across the plate load of tube 10 is applied to the input grid of the power output tube 14 by means of a direct current blocking condenser 15. The input grid of tube 14 is connected to a positive potential point by means of a resistor 16. Assuming that the screen and plate of the output tube 14 are connected to a +250 volt point, the resistor 16 may be connected to a voltage point of approximately +85 volts. The tube 14 may be of the 6AG7 type, although here again

any other well-known form of tube may be used.

The tube 14 is a so-called "cathode follower" amplifier tube. That is to say resistors 6 and 7 are unbypassed, and the load circuit is coupled directly across the cathode resistive load 6, 7. This is accomplished by connecting the primary circuit of audio output transformer 20 in shunt across resistors 6 and 7. A direct current blocking condenser 21 is connected in series with the primary winding of transformer 20. The secondary winding of the audio output transformer may be connected to any desired load, such as a loud speaker. The advantages of using the cathode follower amplifier 14 are the low distortion obtained in the output, and the constant low value of drive impedance at the transformer output terminals.

Actual experimental use with an audio amplifier of the type described provided a reduction in distortion which was relatively great. The frequency response characteristic of the amplifier was substantially flat over a large range of useful audio and superaudio frequencies. By way of specific illustration it is pointed out that the following constants may be employed in connection with the flat response audio amplifier of Fig. 1 it being understood that in the list of constants the symbol "R" designates resistance of the numbered resistor, the symbol "C" designates capacity of the numbered condenser and the symbol "L" designates inductance of the numbered coil:

R₅=400 ohms
R₆=4,000 ohms
R₇=50 ohms
R₁₂=20,000 ohms
R₉=20,000 ohms
R₁₁=500 ohms
C₂₁=1 microfarad
L₁₃=6.3 millihenry

In Fig. 4 I have shown a modification of the cascaded compensation networks wherein they are arranged in push-pull audio amplifier circuits. Thus, the compensation network R₁—C₁ is duplicated. The duplicate network is R'₁—C'₁. The pair of compensation networks R₁—C₁ and R'₁—C'₁ is arranged in the output circuit of a balanced FM detector of the type disclosed by me in my pending application Serial No. 418,927 filed November 13, 1941, U. S. Patent Number 2,351,240 dated June 13, 1944. In this form of balanced FM detector circuit the output load resistors 30 and 31 have the junction thereof at ground potential. Accordingly, the ungrounded ends of the load resistors 30 and 31 are respectively positive and negative in polarity with respect to ground. When the applied signal energy has an instantaneous mean frequency which is equal to the predetermined reference frequency of the discriminator circuit, then the voltages at the free ends of resistors 30 and 31 are of equal magnitude. For frequencies off the mean frequency the ends of resistors 30 and 31 assume potentials of different magnitude. The junction of the compensation networks R₁—C₁ and R'₁—C'₁ is connected to ground.

The audio voltage developed in each of the compensation networks R₁—C₁ and R'₁—C'₁ is applied to a respective input grid of the push-pull audio frequency amplifier tubes 40 and 41 through respective audio frequency coupling condensers 40' and 41'. The tubes 40 and 41 are arranged in well-known push-pull connections. The compensation network R₂—C₂ is duplicated in the output circuit of tubes 40 and 41, and the

junction of the two networks R_2-C_2 and $R'_2-C'_2$ is established at ground potential. In the case of this tube the resistor R_2 of each compensation network R_2-C_2 is fed with positive potential through a respective one of resistors R_3 and R'_3 . It will be recognized that the arrangements are substantially the same as in the case of Fig. 1, but that all circuit elements are duplicated for push-pull operation. The voltages developed across each of the compensation resistors R_2 are fed to a respective one of the push-pull audio amplifier tubes 50 and 51 through respective audio coupling condensers 50' and 51'. The control grid of tube 50 is returned to ground through the direct current return resistor R_5 , while in the case of the control grid of tube 51 there is used the return resistor R'_5 . It will be understood that the plates of tubes 50 and 51 will be connected in push-pull relation. Audio frequency voltage developed in the plate circuits of tubes 50 and 51 will be fed to a push-pull audio amplifier having a flat frequency response characteristic.

By way of illustration, the following purely illustrative values are given for the circuit of Fig. 4, it being understood, of course, that here again the symbols "R" and "C" signify the resistance and capacity respectively of the numbered resistors and condensers:

C_1 and $C'_1=0.004$ microfarad
 C_2 and $C'_2=0.02$ microfarad
 R_1 and $R'_1=100,000$ ohms
 R_2 and $R'_2=20,000$ ohms
 R_3 and $R'_3=100,000$ ohms
 R_4 and $R'_4=1$ megohm
 R_5 and $R'_5=1$ megohm
 R_{30} and $R_{31}=100,000$ ohms

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In an angle modulated carrier wave receiver of the type provided with a demodulator having an output load resistor across which is developed modulation signal voltage whose amplitude is an increasing function over a relatively wide range of modulation frequencies, a modulation signal voltage amplifier, a first resistor and condenser network in shunt with said load resistor and coupled to said amplifier input, the ratio of resistive impedance to reactive impedance of said network being sufficiently high to provide a frequency response at said amplifier input which is inversely proportional to frequency over a portion of said wide range above a predetermined median frequency thereof but which is relatively invariable below said median frequency, a second resistor and condenser network in shunt with said amplifier output, the constants of said second network being chosen to provide a frequency response characteristic which is inversely proportional to frequency over that portion of said wide range below said median frequency but which is substantially invariable over said portion of the range above said median frequency whereby said increasing amplitude is compensated for over said wide range.

2. In an angle modulated carrier wave receiver of the type provided with a demodulator having an output load resistor across which is developed

modulation signal voltage whose amplitude is an increasing function over a relatively wide range of modulation frequencies, a modulation signal voltage amplifier, a first resistor and condenser network in shunt with said load resistor and coupled to said amplifier input, the ratio of resistive impedance to reactive impedance of said network being sufficiently high to provide a frequency response at said amplifier input which is inversely proportional to frequency over a portion of said wide range above a predetermined median frequency thereof but which is relatively invariable below said median frequency, a second resistor and condenser network in shunt with said amplifier output, the constants of said second network being chosen to provide a frequency response characteristic which is inversely proportional to frequency over that portion of said wide range below said median frequency but which is substantially invariable over said portion of the range above said median frequency whereby said increasing amplitude is compensated for over said wide range and a non-frequency discriminatory modulation signal voltage amplifier coupled to said second network.

3. In an angle modulated carrier wave receiver of the type provided with a demodulator having an output load resistor across which is developed modulation signal voltage whose amplitude is an increasing function over a relatively wide range of modulation frequencies, a modulation signal voltage amplifier, a first resistor and condenser network in shunt with said load resistor and coupled to said amplifier input, the ratio of resistive impedance to reactive impedance of said network being sufficiently high to provide a frequency response at said amplifier input which is inversely proportional to frequency over a portion of said wide range above a predetermined median frequency thereof but which is relatively invariable below said median frequency, a second resistor and condenser network in shunt with said amplifier output, the constants of said second network being chosen to provide a frequency response characteristic which is inversely proportional to frequency over that portion of said wide range below said median frequency but which is substantially invariable over said portion of the range above said median frequency whereby said increasing amplitude is compensated for over said wide range, said first network having its resistor connected in series with its condenser, said second network having its resistor connected in series with its condenser, said wide range consisting of the audio frequency range, and said median frequency being substantially 1000 cycles.

4. In combination with a source of audio frequency voltage whose amplitude increases proportionately with frequency over the audio frequency range, an amplifier for the voltage, means operatively associated with the amplifier for compensating for said amplitude increase, said means comprising a first voltage attenuation network, coupling said source to the amplifier input, whose constants are chosen to provide increasing attenuation of audio voltage for audio frequencies of said range above a predetermined intermediate audio frequency but relatively small attenuation below said intermediate audio frequency value, a second voltage attenuation network, coupled to the amplifier output, whose constants are chosen to provide relatively uniform attenuation of said audio voltage for frequencies above said inter-

mediate audio frequency and sharply decreasing attenuation below said latter frequency.

5. In combination with a frequency modulation detector network having input terminals adapted to have applied thereto phase modulated carrier wave energy, an audio output system coupled to the detector, at least two successive compensation networks connected across said audio system, one of said compensation networks consisting of series resistance and capacity whose constants are chosen for rendering the high 10 audio frequency response of the system inversely

proportional to frequency over a portion of the audio range above a relatively low audio frequency but which response is relatively invariable below that low frequency, and the second compensation network consisting of series resistance and capacity whose constants are chosen for rendering the low audio frequency response of the system inversely proportional to frequency for audio frequencies below said low audio frequency and is relatively uniform above the latter frequency.

BERTRAM TREVOR.
